THERAPEUTIC METHOD AND APPARATUS

James K. Forshee, Edwin S. Humphreys, and Earl J. Hasney, Aurora, Ill., assignors to Henry G. Bentson, Aurora, Ill.

Application August 6, 1936, Serial No. 94,642

11 Claims. (Cl. 128—373)

The invention relates to improved therapeutic apparatus and methods of utilizing the same in administering treatments and more particularly to methods and apparatus for fever therapy.

5 Numerous diseases have been found to respond favorably to treatment by artificially induced fever which, in some cases, exerts a direct influence through its bactericidal effect and, in other cases, acts indirectly by stimulating certain 10 body functions, and by increasing metabolism. Various devices have been proposed for producing the fever condition including diathermic devices for transmitting a current of electricity through the body of the patient, and radiotherapy 15 devices in which the patient is placed in an electrical field produced by an alternating current of extremely high frequency. Apparatus has also been proposed for producing fever condition by the external application of heat, and it is with the latter type of apparatus that the invention is particularly concerned.

The field of artificial fever treatment has been somewhat limited by reason of the inherent disadvantages in the apparatus heretofore available. With the electrical apparatus, for example, there is considerable danger of inflicting serious 25 burns on the patient. The apparatus for the direct application of heat has been characterized by the extreme discomfort to which it subjects the patient, largely by reason of the high external 30 temperatures necessary to produce sufficient body temperature to obtain beneficial effects. Moreover, while many of these devices have been more or less effective in producing fever conditions they 35 provide no means for positively controlling body temperatures. As a result, it is frequently found that there is an upward coasting of the patient's body temperature after the application of fever producing energy has been discontinued, with 40 occasional serious and even fatal results to the patient.

With the foregoing in view, it is the general object of the present invention to provide improved methods and apparatus by which the disadvantages above set forth are effectually avoided, and by which the fever treatment may be administered with a minimum of discomfort and in a manner entirely safe to the patient.

Another object is to provide an improved apparatus for administering heat treatment embodying means by which the temperature of the air surrounding the patient may be quickly raised or lowered at will, to provide a more complete and exact control of the patient's body temperature, and to effectually prevent upward coasting

of the same after the desired temperature is reached.

A further object is to provide an improved fever therapy cabinet having in combination with controllable means for supplying heat and moisture, 5 a cooling unit operative to reduce positively the relative humidity of the air in the cabinet.

Other objects and advantages will become apparent from the following detailed description taken in connection with the accompanying 10 drawings illustrating a preferred embodiment of the improved treatment apparatus, in which:

Figure 1 is a longitudinal, sectional view of a heat treatment apparatus embodying the features 15 of the invention.

Fig. 2 is a transverse sectional view taken along the line 2—2 of Fig. 1.

Fig. 3 is a fragmentary plan view of certain 20 of the control instrumentalities shown in Fig. 2.

Fig. 4 is a sectional view taken along the line 20 4—4 of Fig. 1, showing the air conditioning equipment comprising a part of the improved treating apparatus.

Fig. 5 is a schematic representation of the electrical operating and control circuits of the appa- 25 ratus.

Fig. 6 shows a modified form of the air conditioning unit and associated actuating and control mechanism.

Generally stated, the improved therapeutic ap- 30 paratus comprises an elongated cabinet adapted to form a substantially air tight treatment chamber enclosing a portion of the patient's body.

Preferably, the cabinet is of sufficient length to accommodate a patient in a recumbent position, 35 the patient being supported by a suitable cot or stretcher preferably arranged to be moved into and out of the cabinet to facilitate handling of the patient before and after treatment. One of the end members of the cabinet may conveniently comprise a part of the cot assembly where- 40 by the cabinet is closed when the cot is moved into the same and opened when the cot is withdrawn. This end member is provided with a suitable opening through which the patient's head 45 may project during treatment.

Disposed within the cabinet is an air conditioning unit of novel and advantageous construction, automatic control devices for the unit, and means for circulating the conditioned air 50 through the chamber in a manner designed to produce the most favorable reactions in the patient. The air conditioning unit includes a source of heat for heating the cabinet and a source of cold for cooling the same. The latter is a par- 55

ticularly valuable feature, as it permits the temperature of the chamber to be quickly lowered at will, and thus provides a means for accurately controlling the patient's body temperature. Suitable means is included in the air conditioning unit for varying the relative humidity of the air in the cabinet under accurate control. Manually adjustable automatic control mechanism associated with the unit coordinates the operations of the various elements of the unit so that any reasonable desired temperature and humidity conditions may be established and maintained in the chamber. The term "air" as used in the specification and claims is intended to embrace any suitable gas which may be used in the treatment chamber.

- The circulating means provided in the present instance is especially arranged to produce zones of different temperatures within the chamber.
- 5 To this end it includes an air distributing tunnel so arranged that the air is circulated at a comparatively slow rate at the rear end of the chamber, whereby the temperature at that end is maintained substantially above the temperature in 10 the forward end of the chamber. Thus, a greater degree of heat may be applied to the extremities of the patient with highly beneficial results and with a minimum of discomfort to the patient.
- 15 Means is also provided for varying the air pressure in the cabinet either above or below atmospheric pressure. In its preferred form, this means includes a motor driven pump, together with suitable valve mechanism for connecting either the intake or discharge ports of the pump 20 with the cabinet. Adjustable automatic control means is provided in the cabinet for controlling the operation of the pump to avoid undesirable extremes of pressure.
- 25 The therapeutic apparatus above generally described may be utilized to administer heat treatment according to any of the established methods heretofore employed. In addition, the apparatus lends itself readily to an improved method of 30 treatment which is materially safer for the patient and which subjects the patient to a minimum of discomfort while obtaining the full benefits of high body temperatures.

In carrying out the improved method of treatment, the patient is placed in the cabinet which may be substantially at room temperature. The patient is then given a preliminary "humidity" treatment, without any substantial increase in the temperature of the chamber. In this preliminary treatment, the relative humidity of the air in the chamber is built up quickly to between 35 80% and 90% by means of apparatus provided for this purpose in the air conditioning unit. The preliminary treatment stage may be maintained for a period of fifteen minutes or more, as determined by the condition and reactions of the patient. The relative humidity is then quickly reduced to the "comfort zone" which is in the neighborhood of 50% to 55%. At the same time, 40 the heater of the air conditioning unit is started in the operation to raise the cabinet temperature to the desired point, the remainder of the treatment following along the lines of the methods heretofore employed or the improved method 45 to be described hereinafter.

The improved method of treatment above described is particularly advantageous in that it produces reactions in the body which tend to prevent excessive perspiration when heat is applied thereto for inducing a fever condition.

Thus, loss of water and chlorides is materially reduced, and the side reactions to fever such as nausea, tetany, heat prostration, etc., are substantially lessened or prevented.

The improved therapeutic apparatus is particularly advantageous in carrying out an improved "contrast" method of treatment whereby certain body processes may be stimulated and metabolism increased without resorting to the excessive external and body temperatures heretofore required. In accordance with this method, the patient is placed in the cabinet, and if desired, may be given the preliminary humidity treatment above described. The temperature of the cabinet is then raised slightly above body 10 temperature, and is maintained at this point until the patient exhibits a slight fever, as, for example, an increase of approximately one degree above normal body temperature. The cabinet temperature is then lowered rapidly to a point 15 substantially below body temperature and is maintained there until the patient's temperature recedes, preferably an amount somewhat less than the rise obtained by the application of the heat. Application of heat is then resumed, the 20 cabinet temperature being raised slightly above the maximum temperature reached in the previous heating stage and continued until the patient exhibits the desired rise in body temperature, which may be slightly higher than that previously reached. The heat application is followed by another cooling period to reduce the patient's temperature, preferably by an amount somewhat less than the rise obtained in the preceding heating period. This cycle of alternate 25 heating and cooling with corresponding increases and decreases in body temperature is repeated until the desired maximum fever temperature is reached, whereupon the "contrast" treatment 30 may be discontinued and a steady cabinet temperature maintained, or the contrast treatment 35 may be continued further with the patient's temperature being varied between the maximum desired point and a predetermined desired lower point.

It has been found that the alternate increase and decrease in body temperature contemplated by the improved method above described is considerably more effective in increasing metabolism than a straight increase in body temperature 40 such as has heretofore been the practice. The results obtained in experimental uses indicate that the metabolic rate increases substantially as rapidly during the recession of the fever as it does during the increase thereof. Thus, when the primary consideration is simply to increase the metabolic rate, the desired increase may be obtained at a substantially lower body temperature than has heretofore been practical, which 45 is greatly to the advantage of the patient for 50 reasons that will be readily apparent.

Under certain conditions, however, relatively high body temperatures are required to obtain the desired results, as for example the bactericidal effect of a fever condition. It has also been 55 found that, with the "contrast" method of treatment, body temperatures as high as 106 degrees F., can be obtained in a relatively short time with cabinet temperatures not exceeding 115 degrees F., whereas with prior treatment methods 60 and apparatus, cabinet temperatures as high as 160 degrees F., have been the usual thing. The lower cabinet temperatures are much easier on the patient, both from the standpoint of comfort and safety, and for this reason are to be 65 70 75

preferred over the higher temperatures heretofore employed.

Having in mind the foregoing general description of the improved therapeutic method and apparatus, the mechanical construction of the preferred form of apparatus illustrated in the drawings will now be described in detail. Referring to Figs. 1 and 2, the cabinet which forms the treatment chamber comprises a cylindrical metal shell 6, supported in a substantially horizontal position by a metal frame structure or base 7, arranged to rest on the floor A. The cabinet is provided with a metal lining, which, to facilitate assembly, is constructed with an upper section 8, extending around the upper portion and sides of the shell, and a lower portion 9 extending around the lower portion of the shell and overlapping the edges of the section 8 to completely line the shell. The lining is held in spaced relation to the shell 6 by spacing members 10 disposed at opposite ends of the shell, and the intervening space may be filled with suitable insulating material 11 to prevent heat loss.

As herein shown the shell 6 is provided with annular end members 12 and 13 which serve to strengthen the assembly and provide a support for cover plates 14 and 15 closing the front and rear ends of the cabinet, respectively. Each end member is formed with an annular channel 16 adapted to receive the end of the shell, and a packing ring 17 of rubber or other suitable material is wedged into the channel around the shell to provide a substantially air tight seal between the parts. Tie rods 18 extending through the space between the shell 6 and the lining and suitably secured to the end members 12 and 13 hold the parts together to form a sturdy, rigid structure.

To facilitate opening and closing of the cabinet, the end member 12 carries a plurality of hook shaped latch members 19 adapted to contact with quick acting clamping devices 19^a on the cover plate 14, which is utilized to close the front end of the cabinet. A soft rubber gasket 19^a is interposed between the member 12 and the cover plate to provide an air tight seal when the plate is drawn into engagement therewith by action of the clamping devices in cooperation with the latch members. The cover plate 15 which closes the rear end of the cabinet may be bolted or otherwise secured to the end member 13. As herein shown, the plate, is also utilized as a support for an air conditioning unit 20 and other apparatus to be described in detail herein-after.

A suitable cot or stretcher, generally designated by the reference character 21, is provided for supporting the patient in the cabinet in a recumbent position. As shown in Figs. 1 and 2, the cot comprises a pair of elongated side bars 22 joined by cross members 23 and secured at one end to the inner side of the front cover plate 14. The cross members 23 are suitably formed to constitute stretcher supports and to this end are provided with side rails 24 of wood or other suitable material extending longitudinally of the cot. A fabric strip 25 suspended between the side rails provides a comfortable and sanitary support for the patient. To enable the tension of the fabric sheet to be adjusted to meet the requirements of different patients, one of the side rails 24 is mounted on a bracket 26 pivotally supported on the cross member 23 for movement toward or from the other side rail. The bracket 25 is provided with ratchet teeth 27 engageable by

a pawl 28 carried on the cross member 23 and normally urged into engagement therewith by a spring 29, thus locking the bracket in any desired set position.

To facilitate removal and replacement of the fabric sheet 25 so that it may easily be kept in a clean and sanitary condition, means is provided for removably securing the fabric sheet in place on side rails 24. To this end, the lateral edges of the sheet are formed with a hem or fold 25^a, within which is disposed an elongated rod 30 of metal or other suitable material. When the fabric sheet is placed in position, the folds 25^a and their enclosed rods 30 are drawn under the lower edges of the side rails 24 with the rods 30 disposed at the rear thereof. Cam members 31 pivoted on the cross member 23 and bracket 26, respectively, are arranged to clamp the rods 30 against the side rails when in operated position, and thus serve to hold the fabric sheet securely in place. To release the sheet for removal from the cot, the cam members are rocked out of engagement with the rods, thereby releasing the same and permitting removal of the sheet.

The cot 21 is arranged to be moved into and out of the cabinet to facilitate handling of the patient before and after treatment. For this purpose, it is supported at its inner end by rollers 32 journaled on the side bars 22 and arranged to operate on a track formed by rails 33 extending longitudinally of the cabinet. The other end of the cot is secured to the cover plate 14 which, as shown in Fig. 1, is provided with legs 34 equipped with castors 35 adapted to rest on the floor A. Thus the entire cot assembly including the stretcher and the cover plate may be moved easily relative to the cabinet to withdraw the stretcher from the cabinet so that the patient to be placed thereon and to be moved into the cabinet with the patient in place.

Referring more particularly to Fig. 1, it will be observed that the cover plate 14 is especially formed with a view of permitting the patient's head to project from the cabinet during the treatment. To this end, the plate is provided with a suitable aperture 36 in substantial alignment with the top of the cot 21. The central portion of the plate 14 in which the aperture 36 is located is formed to lie at an angle relative to the plane of the plate and thus provide a maximum amount of space adjacent the patient's face in order to make the patient as comfortable as possible. Secured to the outer side of the plate 14 and surrounding the aperture 36 is an annular frame 37 having an inwardly opening channel adapted to provide a seat for an inflatable rubber collar 38 which may be placed around the patient's neck and inflated within the channel. The collar 38 provides a relatively tight seal for the cabinet without subjecting the patient to excessive pressure.

An adjustable head rest is carried on the outer side of the cover plate for supporting the patient's head during treatment. As herein shown, the head rest comprises a fabric strip 39 anchored at one end to a rod 40, carried on the plate 14 and at the other end to a roller 41 journaled on a rod 42 also carried by the plate. A manually operable clamping member 43 operatively associated with the roller 41 is arranged to clamp the roller to the rod to hold the strip 39 in adjusted position.

In the particular construction illustrated in the drawings, the rails 33 constituting the cot

- supporting track are carried on brackets 44 extending transversely of the cabinet and disposed at opposite ends thereof. As will be seen by reference to Fig. 2, the brackets are supported by the 5 tie rods 18 which engage in suitable notches formed adjacent the ends of the brackets. Preferably, the brackets 44 are formed with an arcuate lower edge 45 which rests on the lining 9 to hold the lining in place and prevent it from 10 buckling incident to changes in the temperature of the cabinet. The brackets also carry clamping elements 46 at each end arranged to engage the lower edges of the lining 8 to hold the lining in its proper place.
- 15 In addition to supporting the track rails 33, the brackets 44 are arranged to support an elongated, inverted, generally V-shaped trough 47 which defines an air distributing tunnel extending longitudinally through the cabinet below the 20 cot 21 through which conditioned air is supplied to the cabinet. As will be seen by reference to Fig. 1, the lateral edges of the trough 47 taper from front to rear so as to provide tapering, elongated openings 48 extending along each side of 25 the cabinet. Preferably, the arrangement is such that the width of the opening increases gradually toward the front end of the cabinet so that a greater volume of air is discharged into the front end of the cabinet than is discharged into 30 the rear end thereof. By reason of this arrangement, the air is circulated at a substantially higher rate in the front end of the cabinet and the temperature at that point is materially lower than at the rear end of the cabinet where air is 35 circulated at a slower rate. Thus more heat is applied to the extremities of the patient than is applied to the upper part of the patient's body, which is highly advantageous as heretofore explained.
- 40 The air distributing tunnel formed by the trough 47 and an extension portion or hood 47^a communicates at one end with the air conditioning unit 20 by which the proper temperature and humidity conditions are established in the 45 cabinet. The air conditioning units include a heating element 50, a cooling and de-humidifying element 51, a humidifying element generally designated by the reference character 52 all assembled in a unitary structure and enclosed in a 50 housing providing a system of communicating compartments and passages arranged to direct the flow of air to the various elements in the proper sequence.
- 55 The heating element 50 may be of any suitable type such as the electrically energized resistance heater illustrated. The cooling element 51 likewise may be of conventional construction, the element illustrated being a cooling unit such as is ordinarily used in domestic refrigerators and 60 includes a cooling coil 53 with suitable radiating fins 54. Any suitable means may be employed for supplying refrigerant to the coil 53. In the preferred form of the apparatus, this means comprises a refrigerant compressor 54 arranged 65 to be driven by an electric motor 55. Refrigerant is supplied by the compressor through a duct 56^a to a receiver 58, thence by way of a duct 56 and an expansion valve 57^a to the cooling coil 53, a return duct 57 serving to return the refrigerant to the low pressure side of the compressor. In the present instance, the compressor and associated apparatus are mounted on a shelf 59 mounted on the frame 7 immediately below the cabinet 6.
- 70 75 The humidifying element 52 includes an evap-

orating pan 60 heated by an electrically energized resistance heater 61 of any suitable type. Water is delivered to the evaporating pan through a suitable tube 62 from a storage tank 63. A needle valve 64 is provided to regulate the rate 5 at which water is delivered to the pan and a solenoid operated valve 65 operated by a solenoid 66 is provided for controlling the flow of water from the tank 63. As herein shown the tank is disposed within the cabinet and suitable connections generally indicated by reference character 10 67 are provided to permit filling from the outside of the cabinet and for indicating the amount of water therein.

The system of compartments and passages enclosing the operating elements of the air conditioning unit constitute an important feature of the invention. Referring more particularly to Fig. 4, the heating element 50 is mounted in a compartment 68 connected by a passage 69 with a compartment 70 in which the cooling element 51 is mounted. These compartments are formed by a series of upstanding flanges 71, 72, 73 and 74, preferably cast integrally with the cover plate 15 and arranged to define an elongated rectangular chamber extending generally horizontally across the face of the cover plate. A pair of spaced flanges 75 extend inwardly from the flanges 71 and 73 respectively to define the compartments 68 and 70 and the connecting passage 30 69.

Immediately below the flange 73 is a second chamber 76 formed by a generally arcuate flange 77 connecting at opposite ends to extensions of the flanges 72 and 74. The evaporating pan 60 35 is mounted in this chamber below the compartment 68. Also mounted in the chamber is an electric fan 78 for discharging conditioned air into the air tunnel. As will be seen by reference to Fig. 1, the fan 78 is removably supported on 40 the cover plate 15 so that it may be readily removed for adjustment or repair without disturbing the other elements of the air conditioning unit.

As herein shown, the compartments 68 and 70 45 and the chamber 76 are covered by a plate 79 bolted or otherwise secured to the various flanges. An aperture 80 in the plate 79 in alignment with the fan 78 provides an outlet through which the conditioned air may be discharged into the air 50 tunnel. The plate 79 terminates at the flange 71 thus leaving the space above the compartments 68 and 70 open to the interior of the cabinet, thereby providing an outlet through which the air may be withdrawn from the cabinet for circulation through the air conditioning unit.

Preferably, two separate ports are provided in the flange 71 for withdrawing the air from the cabinet. One port 80 communicates with the heating compartment 68 and the other port 81 60 communicates with the cooling compartment 70. These ports are provided with hinged dampers 82 and 83 respectively, connected by an arm 84 pivoted intermediate its ends on a bracket 85 mounted on the cover plate 15. The arrangement is such that, when one damper is closed, the other is opened, and in the present instance the several parts are so balanced that the damper 83 will move into closed position and damper 82 will open under normal conditions.

Suitable means is provided for opening the damper 83 and closing the damper 82 when required. To this end the damper 83 is provided with a rearwardly extending arm 86 operatively connected by a rod 87 with an armature 88 of a 70 75

solenoid 89. When the solenoid is energized, the armature and connecting rod operate to move the damper 83 into open position and, at the same time, through the operation of the arm 84 the damper 82 is moved to closed position. Thus the air drawn from the cabinet may be directed selectively either through the heating compartment 68 alone or through the cooling compartment 70, passage 69 and heating compartment 68 in series.

As will be seen by reference to Fig. 4, the passage 69 opens into the lower end of the cooling compartment and into the upper end of the heating compartment. The cold air drawn from the 15 cooling compartment is thus circulated over the heating element 50 and discharged through an outlet port 90 into the chamber 76 from which the air is delivered to the air tunnel. A hinged damper 91 at the discharge end of the passage 20 is arranged to prevent the flow of air from the heating compartment to the cooling compartment without interfering, however, with air flow in the reverse direction. In the preferred construction, the evaporating pan 60 is located immediately below the outlet port 90 so that the water vapor produced thereby will be thoroughly mixed with the air before being returned to the cabinet.

It will be apparent that the above construction 30 provides an air conditioning unit capable of delivering air at any reasonable desired temperature and humidity. By opening the damper 82 the air may be circulated over the heating coil alone when desired. If a higher degree of 35 humidity is required, water may be supplied to the evaporating pan 60 so that the heated air will receive additional water vapor. On the other hand, if it is desired to reduce the humidity while increasing the temperature of the chamber, 40 damper 83 may be opened so that the air drawn in from the cabinet is first passed over the cooling coil which, in this case, serves to remove excess moisture therefrom. The moisture thus collecting on the coils of the cooling element may 45 be drained off through a suitable drip pan 92 and drain pipe 93 located below the cooling element.

After being dehumidified, the air is passed over the heating element 50 and discharged into the 50 air tunnel in the usual way. In this case, of course, operation of the humidifying apparatus is discontinued by interrupting the supply of water to the evaporating pan.

When it is desired to quickly reduce the 55 temperature of the cabinet, energization of the heating element 50 may be discontinued and the damper 83 opened so that the air is drawn over the cooling unit 51 and discharged without heating through the outlet port 90. If desired, of course, the cool air may be given an additional 60 moisture content by operating the humidifying apparatus in the usual way.

In the preferred form of the apparatus, automatic control devices are provided for controlling 65 the operation of the various elements of the air conditioning unit so that desired temperature and humidity conditions may be established and maintained within very close limits. These are arranged for accurate manual adjustment to provide a wide range of cabinet temperature and 70 humidity conditions.

Referring to Figs. 2 and 3, the control mechanism includes a suitable thermostatic device 75 94 and a humidostat 95 which for convenience are mounted in a tubular supporting frame 96

projecting into the interior of the cabinet at a point substantially midway between the ends thereof. The thermostatic device may be of any suitable type and as herein shown, includes a mercury bulb 97 connecting with suitable operating mechanism arranged to shift a movable switch member 98 (Fig. 6) into operative engagement with either of two stationary contact members 99 and 100. A manually operable adjusting knob 101 is provided for adjusting the relative positions of the switch arm and contact members so that the device may be set to effect switch closure at any selected temperature. For convenience in effecting this adjustment, a graduated dial 102 is associated with the manual operating member.

The humidostat 95 may be of any suitable type, and in the present instance is mounted bodily within the cabinet. This device includes a movable switch arm 103 engageable with one or the other of two stationary contacts 104 and 105 to complete circuits to be described hereinafter. Manually operable adjusting means is provided for adjusting the device to effect contact closure under the desired predetermined humidity conditions. In the present instance this manually operable means includes a knob 106 carried by a rod 107 having a bevel gear connection 108 (Fig. 2) with the operating element of the humidostat. A graduated dial 109 provides a visual indication 30 of the setting of the device.

As will be seen by reference to Fig. 3, the control apparatus also includes a pressure responsive device 110 arranged to operate suitable switching mechanism for controlling an air pump 35 motor 11 to be described hereinafter. A manually operable knob 112 equipped with a graduated dial 113 is provided for adjusting the pressure device.

As herein shown, the various control instrumentalities and their adjusting mechanisms mounted in a housing 114 secured to the outer shell 6 of the cabinet at a point where the various manual adjusting members may be conveniently reached by the operator of the apparatus. The housing is closed by a cover plate 115 to protect the apparatus, the plate having a suitable window 116 through which the graduated dials 102, 109 and 110 may be viewed.

Referring now to Fig. 5, the operation of the 50 automatic control mechanism will be described briefly. In the embodiment illustrated, power for operating the apparatus is taken from a line 117 through a suitable switch 118, operable manually to open and close the line. The heating element 50 is bridged across the conductors of the line in series with the stationary contacts 99 and the switch arm 98 of the thermostatic device, so that when the temperature of the cabinet reaches a predetermined minimum point, the heating element will be energized. When the temperature of the cabinet rises above the predetermined minimum point, the movement of the switch arm 98 from engagement with the contact 65 99 serves to deenergize the heater. The contacts 99 and 100 are so positioned that, upon a further slight rise in cabinet temperature to a maximum point of, for example, two degrees above the desired temperature, the switch arm engages 70 the stationary contact 100 to complete a circuit for the damper operating solenoid 89. The solenoid opens the damper 83 and closes the damper 82, as previously explained, so that the air drawn from the cabinet is circulated over the cooling 75

element and, since the heating element is deenergized, cold air is delivered to the cabinet.

The humidostat 95 is arranged to control the damper solenoid 89 independently of the thermostat 94 to provide for passing the air over the cooling unit to dehumidify it with the heater either operating or inactive. To this end the switch arm 103 is arranged to engage the stationary contact 104 when the relative humidity reaches a predetermined maximum point. The humidostat also is arranged to control the valve operating solenoid 66 to control the supply of water to the evaporating pan 60. This control is effected by engagement of the switch arm 103 with the stationary contact 105 upon the relative humidity reaching a predetermined minimum point.

In the illustrative embodiment, the heating coil 61 for the evaporating pan is connected directly across the power line so that the coil is energized at all times during the operation of the apparatus. To prevent over-heating of the pan, a thermostatic switch 119 is provided. This switch may be of any suitable type and is preferably connected in series with the heating unit 61.

The refrigerant compressor motor 55 is connected directly across the power line so that the cooling unit is available for use at all times when the switch 118 is closed. In order to maintain the temperature of the cooling element 51 at a uniform low temperature, a thermostatic switch 120 of conventional type is connected in series with the compressor motor. As shown in Fig. 4, this switch may be attached directly to the cooling coil of the element 51 in accordance with the usual practice in commercial refrigeration.

The electric fan 78 is also connected directly across the power line so that the fan operates at all times when the main switch 118 is closed. Thus, the air is circulated through the air conditioning unit and cabinet at all times when the apparatus is in use.

In the preferred form of the apparatus, the air pump motor 111 is connected to the power line through suitable switching mechanism controlled by the pressure responsive device 110 and a manually operable switch 121. The latter switch provides for disconnecting the pump motor without interfering with the operation of the air conditioning unit when treatments are given at normal atmospheric pressure. The switch mechanism is arranged to stop the motor when a predetermined cabinet pressure either above or below atmospheric pressure is attained and thus guards against excessively high or low pressure in the cabinet.

As herein shown, the motor 111 is arranged to drive a suitable air pump 122 having an intake or suction line 123 and a discharge or pressure line 124. These two lines are connected to opposite ports of a four-way valve 125 which, in the present invention, is arranged for manual operation. One of the intermediate ports of the valve 125 is open to the atmosphere and the other is connected by a tube 126 with the interior of the cabinet. Thus, by operating the valve, either the suction line 123 or the pressure line 124 may be selectively connected with the cabinet so that the pump 122 will be effective to raise or lower the cabinet pressure as determined by the setting of the pressure responsive device 110.

As shown in Fig. 1 of the drawings, the tube 126 enters the cabinet through an aperture 127

formed in the lining 9 and shell 6. A tubular member 128 secured to the shell 6 below the aperture and enclosing the end of the tube provides an air tight seal for the same and forms a well for receiving any water that may collect in the cabinet due to condensation or the like. A drain pipe 129 equipped with a valve 130 provides a convenient means of draining the collected water from the well.

Having in mind the construction and arrangement of the various elements of the preferred form of treatment apparatus above described, the operation of the apparatus and particularly of the air conditioning unit and automatic control devices will now be discussed briefly. By way of example, it will be assumed that a patient has been placed in the cabinet and that the front cover plate 14 has been clamped in place. The cabinet may be at ordinary room temperature, as for example, 75 degrees F.

In the event that the patient is to be given the preliminary humidity treatment, the thermostat 94 will be set for the room temperature while the humidostat 95 is set for a relative humidity of say 85%. When the main switch 118 is closed, the fan 78 and refrigerating motor are started and the heater 61 of the evaporating pan is energized. By reason of the adjustment, switch arm 103 of the humidostat engages contact 105 to close a circuit for the valve solenoid 66. The solenoid opens the valve 65 permitting water to flow from the tank 63 to the evaporating pan 60, the rate of flow and thus the time required to attain the desired degree of humidity depending upon the setting of the needle valve 64. The water vapor thus produced is mixed with the air and circulated through the cabinet by the fan 78. When the proper degree of humidity is reached, the switch arm 103 moves out of engagement with contact 105 thereby interrupting the circuit of the valve solenoid and permitting the valve to close and shut off the flow of water to the evaporating pan.

At the end of the preliminary treatment period, the humidostat is manually set back to a lower point, as for example 50% relative humidity. Since the relative humidity of the air in the cabinet is above this point, switch arm 103 will engage the stationary contact 104 thereby completing the circuit for the damper operating solenoid 89. The solenoid opens the damper 83 and closes damper 82 so that the air drawn from the cabinet is circulated over the cooling element 51 which is maintained at a low temperature by the operation of the compressor 54 under control of the thermostat 120. Contact with the cooling element cools the air below the dew point, the moisture condensing on the coils of the element and the dehumidified air passing on through the unit and back to the cabinet. When the proper degree of humidity is attained, switch arm 103 moves away from the contact 104 to deenergize the damper solenoid and permit the dampers to return to their normal positions with damper 82 open and damper 83 closed.

At the same time the humidostat is set back, the thermostat 94 may be adjusted to call for an increase in cabinet temperature to 100 degrees F., for example. As a result of this adjustment, switch arm 98 engages contact 99 to energize the heating element 50 whereby the dehumidified air discharged from the cooling compartment is heated and the cabinet is raised to the desired temperature. When the cabinet temperature reaches 100 degrees F., the switch arm moves

away from the contact to deenergize the heater.

Cabinet temperature is maintained at the desired point with slight variations under control of the thermostat 94. When the temperature falls below this point, the heater is energized by the engagement of the switch arm 98 and contact 99. In case the temperature rises to a predetermined maximum point which may be a degree or so above the desired temperature, the damper solenoid will be energized to introduce cold air into the cabinet due to switch arm 98 engaging contact 100. When the temperature falls to the desired point, the damper solenoid is deenergized to discontinue the supply of cold air to the cabinet.

When it is desired to lower the cabinet temperature, the thermostat 94 is set accordingly and operates to deenergize the heating element 50 and energize the damper solenoid 89. During these temperature changes, the humidostat 95 operates to automatically maintain the proper degree of humidity in the cabinet.

The above described operations may be carried on at normal atmospheric pressure or at pressures either above or below such normal pressure by placing the air pump 122 in operation. In this case, the pressure responsive device 110 will be manually set to maintain the desired pressure in the cabinet.

The modified form of the air conditioning unit shown in Fig. 6 is designed to provide means whereby extremely rapid cooling of the treatment chamber may be effected with a refrigerating unit of relatively small capacity. To this end, the refrigerant compressor 54 is arranged to supply refrigerant to a cooling coil 131 disposed in a storage tank 132 containing a suitable fluid such as oil or the like having a low freezing point. A pump 133 driven by an electric motor 134 is arranged to circulate the cooled fluid from the storage tank through the cooling element 51.

With this arrangement, the fluid in the storage tank may be cooled to a very low temperature during the idle periods of the treatment apparatus. Thus, a large volume of pre-cooled fluid is available for immediate use when required, permitting the cooling element 51 to be operated at a substantially lower temperature than is practicable with the compressor directly connected thereto and thereby providing a convenient means for very quickly cooling the treatment chamber.

The storage tank 132 may be of metal or of other suitable material and is preferably covered by a thick layer of insulating material 135 to prevent thermal losses. The insulating cover may be covered by a suitable casing 136. With this arrangement, the thermostat 120 for controlling the operation of the refrigerant compressor motor 55 is mounted in the storage tank.

As will be seen by reference to Fig. 6, the housing for the air conditioning unit 20 is simplified in the modified form of the apparatus by omission of the inlet port 80 of the heating compartment 68 and utilizing the inlet port 81 exclusively for withdrawing air from the treating chamber. Likewise the dampers 82 and 83 and the associated damper operating mechanisms are dispensed with.

In the present instance, the cooling element 51 is rendered effective only when it is required to cool the treating chamber or to reduce the humidity thereof. To this end, a solenoid 89 connected in the control circuit in the same manner as the solenoid 89 is arranged to control the

operation of the pump motor 134. The solenoid is energized under control of the thermostat 94 when the thermostat calls for less heat in the treating chamber and also under control of the humidostat 95 when the latter calls for a lower humidity. A switch 135 is closed by the solenoid when energized to complete the circuit for the motor 134. The other elements of the control system operate in the same manner as in the preferred embodiment hereinbefore described.

It will be apparent from the foregoing that the invention provides new and useful methods and apparatus for fever therapy. By utilizing the improved methods, the full benefits of the fever treatment may be obtained with a minimum of discomfort and in a manner entirely safe to patient. The loss of water and chlorides is materially reduced and the side reactions to fever are substantially lessened or prevented. Moreover, metabolism may be increased and other body functions stimulated at external and body temperatures substantially lower than heretofore required for equivalent results.

The apparatus provided for carrying out the improved and other therapeutic methods is efficient and reliable in operation and is subject to extremely accurate control. It includes novel and useful structural features which greatly facilitate the handling of patients. It also includes air conditioning apparatus of improved construction, together with manually adjustable automatic control mechanism providing great flexibility of adjustment with extremely accurate control. The temperature to which the patient is subjected may be quickly raised or lowered at will. Humidity conditions may also be varied as desired to produce the most beneficial results.

We claim as our invention:

1. A therapeutic fever apparatus comprising, in combination, a cabinet having a chamber confining a body of air and adapted to receive the body of a patient to be treated, means for producing a forced circulation of the body of air in the chamber, controllable means for supplying heat to the circulating body of air, controllable moisture supply means for increasing the moisture content of the air, and means comprising a cooling unit interposed in the path of the circulating air and operative when the heat and moisture supply means are cut off to effect a rapid and substantial reduction in the temperature and relative humidity of the air in the cabinet.

2. A therapeutic fever apparatus comprising, in combination, a cabinet having a chamber confining a body of air and adapted to receive the body of a patient to be treated, means for producing a forced circulation of the body of air in the chamber, controllable means for supplying heat to the circulating body of air, controllable moisture supply means for increasing the moisture content of the air, and means including a cooling unit operative when the heat and moisture supply means are cut off to effect a reduction in the temperature and a rapid and substantial reduction in the relative humidity of the whole body of air in the cabinet.

3. The method of artificially inducing and controlling fever in the human body which comprises subjecting the body of a patient under treatment to a confined circulating body of air, supplying heat and moisture to the air, to induce a desired degree of fever, and when the fever induced exceeds the desired degree rapidly and substantially cooling the confined body of air in the course of its circulation to reduce its temperature

and to sharply reduce its relative humidity and then recirculating it over the patient.

4. The method of inducing and controlling fever in the human body which comprises subjecting the body of the patient to be treated to a circulating current of moist air heated to a temperature sufficient to induce fever in the body, and effecting a sudden and substantial drop in the relative humidity of the air circulated over

10 the body to prevent an undesired increase in the internal temperature or pulse rate of the patient.

5. The method of artificially inducing and controlling fever in the human body which comprises subjecting the body of a patient under treatment

15 to a circulating body of air heated to a temperature of from 110° to 120° F., adding moisture to the air, and when the fever induced exceeds a desired degree suddenly reducing the relative humidity and also reducing the temperature of

20 the air to which the patient is subjected whereby to check an upward coasting of the patient's internal temperature.

6. The method of artificially inducing and controlling fever in the human body which comprises

25 circulating a body of air over the body of a patient under treatment, initially maintaining the air circulating over the patient's body at a temperature substantially above normal body temperature and maintaining such air at a high relative humidity of the order of 80 per cent, and after such initial period continuing the temperature of the air flowing over the patient's body at a point substantially above normal body temperature but with the humidity of the air decreased to

30 an intermediate value of the order of magnitude of 50 per cent relative humidity.

7. A method of fever therapy for human beings in which at least a portion of the patient's body

40 is heated to a temperature above normal body temperature in a closed chamber, which includes the step of checking sudden and inadvertent rises in the patient's body temperature and pulse rate above predetermined levels during the course of the treatment by artificially chilling a body of

45 air to a temperature substantially below ordinary room air temperature of the order of 75° F. to dehumidify the same to value of relative humidity sharply below that previously prevailing in the air about the patient and circulating the dehumidified air over the patient until the patient's

50 pulse and body temperature are reduced to a desired point.

8. The method of fever therapy for human

beings in which the major portion of the patient's body including the torso and limbs is disposed in a closed chamber, which comprises circulating heated air of high relative humidity over the body of the patient until an artificial fever of desired 5 degree is attained, then passing the circulating body of air in said chamber over a cooling unit having a temperature substantially below the freezing point of water so as to reduce the temperature of the air passing over the patient's body and at the same time extract moisture from the air to reduce sharply the humidity thereof, and continuing the circulation of said body of air over the cooling unit and the body of the patient successively until the patient's pulse rate and body temperature are reduced to a desired point.

9. A method of fever therapy for human beings in which at least a portion of the patient's body is heated to a temperature above normal body temperature by circulating about it a confined body of heated air, which includes the step of cooling and reducing the relative humidity of the confined body of air before recirculating it over the patient by passing it through a refrigerating unit in order to accurately and precisely control the temperature and relative humidity to which the patient is subjected within any desired limits irrespective of prevailing outside temperature and humidity conditions.

10. In a therapeutic apparatus the combination 30 with a closed chamber dimensioned to receive the body of a patient, and means for heating the air confined within the chamber and circulating it over the patient's body to induce a fever therein, of means for artificially cooling and reducing the relative humidity of the air trapped in the closed chamber and recirculating it over the patient.

11. In a therapeutic apparatus the combination 40 with a closed chamber dimensioned to receive the body of a patient, and means for heating the air within the chamber and circulating it over the patient's body to induce a fever therein, of a storage reservoir adapted to contain a body of low freezing point liquid, refrigerating means for cooling the liquid in the reservoir to impart to 45 it a large heat absorbing capacity, and means for circulating air from the chamber in heat exchange relation with the chilled liquid to sharply dehumidify the air and for then recirculating it into the chamber.
